UNITED STATES PATENT OFFICE.

CALVERT B. COTTRELL, OF STONINGTON, CONNECTICUT.

INKING APPARATUS FOR PRINTING-MACHINES.

SPECIFICATION forming part of Letters Patent No. 385,098, dated June 26, 1883.

Application filed August 12, 1887. Serial No. 246,761. (No model.)

To all whom it may concern:

Be it known that I, CALVERT B. COTTRELL, of Stonington, in the county of New London and State of Connecticut, have invented a new and useful Improvement in Inking Apparatus for Printing-Machines, of which the following is a specification.

My invention is applicable for drum or two-revolution printing machines or presses; and an important object of the invention is to locate the ink-fountain and the inking apparatus generally so as to provide for ready access to the form or for the removal of the form-inking rollers.

15 In carrying out my invention I support the ink-fountain and roller upon brackets which project from and are secured to the cylinder-frames, so as to afford free access to the form and other parts beneath the fountain. The 20 ink is delivered from the fountain-roller by a vibrating or movable ductor-roller to a series of distributing-rollers, some of which vibrate longitudinally, and these distributing-rollers deliver the ink to the form-rollers. The several 25 distributing-rollers are mounted in stand-tops or side frames having hand-connections—such as eccentrics—and a hand-lever, whereby the side frames with the distributing-rollers may be lifted clear of the form-rollers, so as to 30 permit access to them or to permit of the removal of the form-rollers. Upon a shaft—as, for example, one of the journals of the main drum or cylinder—is a cam which through a 35 rock-shaft transmits motion to those of the distributing-rollers which vibrate lengthwise, and in order to maintain the arm of the rock-shaft in constant engagement with said cam, notwithstanding the rising and falling movements which may be given the roller-frame, I 40 support the rock-shaft in a pipe-bearing which is fitted to said roller-frame, all as more fully hereinafter described.

The invention consists in novel combinations of parts particularly hereinafter described, and pointed out in the claims.

45 In the accompanying drawings, Figure 1 is a side elevation of such parts of a machine as are necessary to illustrate my invention. Fig. 2 is a plan thereof, the cylinder or drum being in horizontal section. Fig. 3 is a sectional elevation in a plane transverse to the axis of the

cylinder and indicated by the dotted line *xx*, Fig. 2.

Similar letters of reference designate corresponding parts in the several figures. 55

A designates the cylinder or drum, which is provided with journals *a*, mounted in bearings *b* in suitable cylinder or side frames, B; and C designates the form-rollers, which rotate by contact with the form upon the bed, 60 which passes beneath them, and is not here shown.

D designates an ink-fountain, which, as usual, is provided with a fountain-roller, *d*, and this ink-fountain is mounted upon brackets *D'*, which are secured to and project from the cylinder-frame B at a considerable elevation above the main frame of the press, so that free access is afforded beneath the ink-fountain and beneath the brackets *D'* to the 70 form, and also to the form-rollers C. The fountain-roller *d*, as is usual, has upon its shaft a hand-lever, *d'*, carrying a pawl, *d''*, and which is operated by a rod, *d'''*, from an arm, *d''*, which is pivoted at *d'*, and upon which acts 75 a cam, *d''*. The action of the cam *d''*, bearing on the truck-roller *d'*, serves to vibrate the lever or arm *d'* backward and forward, and, through the pawl and ratchet, turns the fountain-roller *d*.

e designates a ductor-roller, which is mounted 80 on a lever, *E*, fulcrumed at *e'*, and carrying at its opposite end a truck-roll, *e''*, upon which acts a cam, *E'*, secured to the end of the cylinder. This cam *E'* acts to move the ductor *e* alternately into contact with the fountain-roller *d* and with one of a series of distributing-rollers, *f*, which bear one on another, and the lowermost one of which bears upon the form-rollers C. Certain of the distributing-rollers *f* vibrate lengthwise in a well-understood manner, and are provided upon their journals with grooved heads *f'*, with which engage pins or projections *f''* upon the arms *f''*, which project in opposite directions from a rock-shaft, *F*, and at its opposite end this rock-shaft *F* has an arm, *f''*, which engages a grooved cam, *F'*, upon one of the cylinder-journals *a*. It will therefore be seen that, as the cylinder and its journal rotate, the grooved cam *F'* imparts a rocking or vibrating motion to the 90 rock-shaft *F*, and through the arms *f''*, engaged with the grooved heads *f'* of the rollers

f, a longitudinally-vibrating motion is imparted to such rolls and the ink is distributed. I have shown the rollers *f* as journaled in a frame or stand-top, *F*², which is fulcrumed at 5 *f*⁵, and by suitable hand-connections the said frame *F*² may be raised and lowered and held in either of its two extreme positions. As here shown, the hand-connections consist of a shaft, *G*, extending across the machine and 10 having upon it two eccentrics, *g*, the rods *g*' of which are connected with the frames *F*², and upon the shaft *G* is also applied a handle or arm, *G*', by which the shaft may be turned and the eccentrics shifted a half-revolution, 15 so as to stand at either of their dead-points, in which positions they hold the frame *F*² either elevated, so that its rollers *f* are entirely out of contact with the form-rollers, or depressed, so that its rollers are in contact 20 with said form-rollers.

It is obvious that when the frames *F*² are raised by the hand-connections described the rollers *f* would, unless means were employed to prevent, be moved out of proper working relation to the rock-shaft *F*; and to prevent this I mount the rock-shaft in a long pipe bearing or box, *F*³, which is bolted to the frame *F*², and the arm *f*⁴ has enough play in the cam so as to permit the frame *F*² to be moved without disengaging the crank pin or arm *f*⁴ from the cam *F*'. Consequently, when the frame *F*² is raised or lowered, the rock-shaft *F* is simultaneously moved, and the arms *f*³ are always held in engagement with the grooved heads 30

f' of the rollers *f*, while the arm *f*⁴ is also 35 maintained in engagement with the grooved cam *F*'. Whenever the frame *F*² and its rollers *f* are raised by the action of the eccentrics and shaft *g* *G*, the rollers *f* are freed from contact with the rollers *C*, and the rollers *C* can 40 be manipulated and removed or replaced, or access can be had to them for any other purpose.

What I claim as my invention, and desire to secure by Letters Patent, is—

1. The combination, with the cylinder and form-rollers for acting upon the form, of a movable frame or stand-top wherein are journaled the vibrating and other distributing rollers, a cam and rock-shaft for vibrating 50 said rollers, and a bearing for the rock-shaft secured to the movable frame and serving to maintain the rock-shaft in engagement with its operating cam, substantially as herein described.

2. The combination, with the cylinder *A* and the form-rollers *C*, of the swinging frame *F*², carrying the distributing-rollers *f*, the eccentrics *g*, for moving said frame, the cam *F*', and the rock-shaft *F*, for vibrating certain of the 60 rollers *f*, and the box *F*³ for said rock-shaft, secured to the swinging frame, substantially as herein described.

CALVERT B. COTTRELL.
